(57) **CLAIM**

The ornamental design for the tattoo chair, as shown and described.

DESCRIPTION

FIG. 1 is a front perspective exploded view of a tattoo chair showing our new design in an upright configuration.

FIG. 2 is a rear perspective view thereof without the front head rest attachment shown.

FIG. 3 is a rear elevational view thereof.

FIG. 4 is a front elevational view thereof.

FIG. 5 is a right side elevational view thereof.

FIG. 6 is a left side elevational view thereof.

FIG. 7 is a top plan view thereof.

FIG. 8 is a bottom plan view thereof.

FIG. 9 is a front perspective view of a tattoo chair showing our new design in reclined configuration.

FIG. 10 is a rear perspective view of FIG. 9.

FIG. 11 is a rear elevational view of FIG. 9.

FIG. 12 is a front elevational view of FIG. 9.

FIG. 13 is a right side elevational view of FIG. 9.

FIG. 14 is a left side elevational view of FIG. 9.

FIG. 15 is a top plan view of FIG. 9; and,

FIG. 16 is a bottom plan view of FIG. 9.

The broken lines showing structural support and removable armrests are for the purpose of illustrating environmental structure and form no part of the claimed design.

1 Claim, 13 Drawing Sheets
